UNITED STATES PATENT OFFICE.

GEORGE HEGEMAN HAERT, OF WEST HARTFORD, CONNECTICUT.

ELECTRIC TIME SWITCH.

Application filed March 4, 1927. Serial No. 172,661.

This invention relates to apparatus for controlling an electric circuit or circuits, and has as its aim to provide a device or apparatus of this sort having various features of 5 novelty and advantage.

One object of the invention is to provide an improved timing mechanism by which a current or currents may be automatically thrown on and off at predetermined times, 10 this timing mechanism being very simple and compact in construction, economic in manufacture, and effective in operation.

A further object is to provide a timing mechanism of this sort which is extremely 15 simple in its manipulation or setting, so that an unskilled person, such, for instance, as a housewife, may expeditiously set the same with nicety and without becoming confused by making unnecessary calculations.

20 Other objects will be in part obvious and in part pointed out more in detail hereinafter.

The invention accordingly consists in the features of construction, combination of elements and arrangement of parts which 25 will be exemplified in the construction hereinafter set forth, and the scope of the application of which will be indicated in the appended claims.

As an instance of a use to which the improvements of the present invention may be applied, reference may be had to an electric cooking range wherein it is desirable to automatically throw the current onto and off of the heating element or elements at predetermined times. It is to be understood that the 30 present disclosure is by way of illustration only, and that my improved timing mechanism may be used otherwise than in combination with a range.

40 In the accompanying drawings:

Figure 1 is a front elevational view of my improved timing mechanism, the casing therefor being omitted;

Fig. 2 is a view taken vertically and centrally through the mechanism;

Fig. 3 is a view similar to Fig. 1 but with the knob or handle for setting the device omitted and the dials being shown in position at which the timing mechanism is 50 operative;

Fig. 4 is a view of the dial per se;

Fig. 5 is a view of the disk which is adapted to abut against the rear face of the dial; and

55 Fig. 6 is a detail view of a spring plate for urging the disk against the dial.

The timing mechanism includes suitable driving means, such as a clock or recorder movement, which is not shown in detail as the particular construction thereof is immaterial, it being sufficient to state that it may have a train of gears (not shown) and a spring 10 for driving the train. In the present instance, this recorder movement is shown as housed within a shell 11 and as 60 having a shaft 12 which is preferably driven in a counterclockwise direction one complete revolution each twenty-four hours or at any other rate depending on the selected markings on the dial to be hereinafter described. 65 Secured to the shell is an insulating plate or base member 15 which carries a pair of contacts 16 and 17 and a terminal 18, the latter being electrically connected by a spring 19 to a switch plate 20 pivoted as at 21. The 70 switch plate has a contact or tongue 22 which is adapted to engage the contacts 16 and 17. This switch plate also carries a roller 23 which is adapted to engage against the peripheries of the dial A and the disk B. One 75 of the contacts, for instance the contact 17, may be connected up to the opening coil of a magnetic switch (not shown) in such manner that when the switch plate is in engagement with the contact 17, as shown in Fig. 1, 80 the circuit through the heating element or elements of the range (also not shown) is broken. The other contact 16 may be connected to the closing coil of the magnetic switch in such manner that when the switch plate is in engagement with this contact, a 85 current will flow through the heating element or elements of the range.

The switch plate 20 is controlled in its movements by a pair of disks, one comprising 90 the dial A having means for controlling the throwing of the switch into one condition, in the present instance into engagement with the contact 17. The other disk comprises the generally circular member B back of, and 95 frictionally engaging the rear face of, the dial and having means for controlling the throwing of the switch into the other condition, i. e., into engagement with the contact 16. The disk B has a portion 25 of larger 100 radius adapted to engage and hold the switch plate in the position shown in Fig. 1. The rear edge 25 of this portion of larger radius is preferably inclined and its position determines the time at which the switch plate is 105 thrown into engagement with the contact 16. The extent of the reduced portion 26 of the 110

disk may be varied to suit requirements, but, by way of illustration, this portion is shown as being of such extent as to provide a cooking period of, at least, ten hours. The dial 5 A has a portion 27 of larger radius and a reduced portion 28, the latter preferably being at least as great in extent as that of the reduced portion 26. In the present instance, these reduced portions 26 and 28 are of the 10 same radius, but one may be of lesser radius than the other. Adjacent one end of the portion 27 of the dial is a notch 29, in which the roller 23 is engaged when it is desired to render the timing mechanism inoperative as, for instance, when it is desired to cook without employing the timer. The forward edge 27' of the portion 27 is preferably inclined and constitutes a cam, so to speak, for controlling the throwing of the switch plate 15 from engagement with the contact 16 and into engagement with the contact 17. The dial also has a projection 30, the front face of which is abrupt and the rear face of which is inclined. The dial is provided on its front 20 face with suitable numerals chronologically arranged counterclockwise. In the present illustrative disclosure, these numerals are employed to indicate in hours the angular movement of the dial.

25 The dial A and the disk B are angularly adjustable on the shaft 12 and are adapted to rotate with that shaft when the clock mechanism rotates the latter in a counterclockwise direction. In the present instance, the dial is connected by means of rivets 35 to a flange 36 of a sleeve 37 journalled on the shaft 12 and connected thereto by means of a friction clutch. This clutch may include the flange 36 and a ring 38 normally urged 30 against the flange by a coiled spring 39. If desired, there may be interposed between the flange 36 and the ring 38 a lining 40. Between the flange 36 and the dial A is a spacing washer 41 which forms a bearing for the 35 disk B. The numeral 42 designates a spring plate interposed between the flange 36 and the spacing washer 41 and having, as most clearly shown in Fig. 5, spring fingers 43 adapted to engage against the disk B and frictionally urge the same into engagement 40 with the rear face of the dial.

45 The dial A is angularly adjusted relative to a fixed pointer 45 so as to set the mechanism to throw the switch plate, at a predetermined time, into one position, in the present instance, into engagement with the contact 17; and the disk B is angularly adjusted relative to the dial so as to set the mechanism to throw the switch at a predetermined time 50 in the other position by turning a single handle or knob 46. This handle or knob is freely journalled on the sleeve 37 and is normally urged against a glass plate 47 by a spring 48, the outer end of which abuts against a washer 49 secured on the outer end of the shaft by a 55 screw 50. The handle is connected to the disk B by a pin 51 secured to this disk and extending into a recess in the handle, as most clearly shown in Fig. 3. The pin extends through an arcuate slot 52 in the dial. The 60 numeral 53 designates an indicator connected to the disk B so as to be adjusted therewith and thereby indicate the setting of the disk relative to the dial. This indicator is positioned between the dial and the glass plate 65 47; it is journalled on the sleeve 37, and is connected to the disk by the pin 51. In the present illustrative disclosure, the arrangement is such that the switch plate may be held by the spring 19 in engagement with the contact 16, for a maximum period of ten hours, but it is, of course, understood that any maximum period may be adopted. A maximum period of ten hours having been assumed, the length of the slot 52 in the dial 70 is such that the disk B may be adjusted relative to the dial a maximum angular distance 75 which is indicated by ten hours on the dial.

80 The operation of the mechanism is briefly as follows: Assuming that it is twelve o'clock noon, and a housewife wishes to cook a dish for two hours and serve the same at six o'clock, she would calculate that a period of six hours is to elapse between the time of setting and the end of the cooking period, and 85 she would, therefore, turn the handle 46 clockwise until the numeral six of the dial registered with the pointer 45, as shown in Fig. 1. It will be seen that when the handle is turned clockwise, the dial A and the disk 90 B are rotated clockwise through the connection formed by the pin 51, the latter being in engagement with the rear edge of the slot 52. After the dial has thus been set, the handle is rotated counterclockwise (without 95 moving the dial) until the indicator 53 is in registry with the numeral two of the dial, that is, to the position shown in Fig. 1. The apparatus having been set as described, the 100 train of gears of the clock will rotate the shaft 12 and the parts mounted thereon counterclockwise. When four hours have elapsed, that is, at four o'clock p. m., the rear edge 105 25' on the disk will permit the roller to ride off of the portion of larger radius 25, whereupon the spring 19 will throw the switch plate so that the tongue 22 engages the contact 16. For the next two hours, that is, between four and six o'clock, which is the assumed desired cooking period, the switch will 110 remain in the position in which it has been thrown. When six hours have elapsed, the forward edge 27' on the dial will cam the switch plate to the position shown in Fig. 1, thus breaking the circuit through the heating element of the range where the device is 115 used in such combination. At this time, the projection or stop 30 comes into engagement with the pointer 45 so as to prevent further rotation of the dial and thus the dial is held 120 125 130

in a position where the portion 27 of the dial maintains the switch plate in the position shown in Fig. 1.

It may be desirable to use the range without employing the automatic time control, in which event, it is necessary to hold the switch plate in a position at which current flows through the heating element. To this end, the dial has a notch 29 in which the roller 23 is adapted to engage, as shown in Fig. 3. When the roller is thus engaged in this notch, the dial is held against rotation. That portion of the dial which is adjacent the pointer 45 when the roller is in the notch 29 may be appropriately marked, as, for instance, "cooking without timer," as indicated in Fig. 1 of the drawings. The rear edge of the projection 30 is inclined so that, when the handle is rotated clockwise, this stop may 20 ride beneath the pointer 45.

It will be observed, from the foregoing description taken in connection with the accompanying drawings, that my improved arrangement is extremely simple in construction and manipulation. The apparatus may be very simply set by one who is not at all mechanically inclined or who does not in any way understand the structure or functioning of the device. The disk B is behind, and concealed in large part by, the dial. The entire face of the dial is uncovered so that it can be observed. The indicator, which is in front of the dial, does not interfere with the readings thereof and accurately indicates the adjusted position of the disk. In setting the timer, there are only two movements necessary, namely, that of setting the dial so as to indicate the lapse of time between the setting and the end of the cooking period, and 40 then setting the indicator in accordance with the desired cooking period, and both of these settings may easily be had by turning the single handle 46 and without mental calculations.

As many changes could be made in the above construction and many apparently widely different embodiments of this invention could be made without departing from the scope thereof, it is intended that all matter contained in the above description or 50 shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language might be said 60 to fall therebetween.

I claim as my invention:

1. In a time switch, driving means, a switch, a dial rotated by said driving means and angularly adjustable relative thereto, 65 said dial having means for controlling the

throwing of said switch into one condition at any predetermined time, an indicator rotated in unison with said dial by said driving means, said indicator being angularly adjustable with respect to said dial, means movable with said indicator for controlling the throwing of the switch into another condition at any predetermined time, a fixed pointer cooperating with said dial, and a single handle for adjusting said indicator and dial. 70 75

2. In a time switch, driving means, a switch, a dial rotated by and adjustable relative to said driving means and having means for controlling the throwing of said switch into one condition at any predetermined time, 80 said dial having numerals thereon chronologically arranged in a direction reverse to that in which said driving means rotates said dial, an indicator angularly adjustable relative to said dial and movable in unison therewith when the same is rotated by said driving means, said indicator having fixed thereto means for controlling the throwing of said switch into another condition at any predetermined time, a pointer cooperating with the numerals on said dial, and a rotatable handle for adjusting said indicator and dial. 85

3. In a time switch, a switch, driving means, a dial rotated thereby and angularly adjustable relative thereto, said dial having 90 means for controlling the throwing of said switch into one condition at any predetermined time, an indicator rotated in unison with said dial by said driving means and angularly adjustable relative to said dial, an element movable with said indicator for controlling the throwing of the switch into another condition at any predetermined time, 95 a fixed pointer cooperating with said dial, and a rotatable handle connected to said indicator and said element for setting the same, said handle having a limited angular movement relative to said dial whereby said indicator and element may be adjusted relative to the dial and the dial may be adjusted by turning said handle. 100 110

4. In a time switch, driving means, a switch, a dial rotated by said driving means and having means for controlling the throwing of said switch into one condition at any 115 predetermined time, an indicator angularly adjustable relative to said dial and movable therewith when the dial is rotated by said driving means, said indicator having connected thereto means for controlling the 120 throwing of the switch into another condition at any predetermined time, a fixed pointer cooperating with said dial for indicating the setting thereof, a handle connected to said indicator for adjusting the same, and a pin 125 and slot connection between said handle and dial.

5. In a time switch, a switch, driving means, a dial rotated by and angularly adjustable relative to said driving means and 130

having means for controlling the throwing of said switch into one condition, a disk rearwardly of said dial and having means for controlling the throwing of said switch into another condition, an indicator in front of said dial and connected to so as to rotate with said disk, said indicator and disk being angularly adjustable relative to said dial and movable in unison therewith by said driving means, and a handle connected to said indicator and having limited angular movement relative to said dial whereby said indicator and disk may be adjusted relative to said dial, and said dial may be adjusted by turning said handle.

6. In a time switch, a switch, driving means, a rotatable adjustable dial rotated by said driving means and having means on its periphery for controlling the throwing of said switch into one condition at any predetermined time, a disk rearwardly of said dial adjustable relative thereto and having means on its periphery for controlling the throwing of said switch into another condition at any predetermined time, an indicator in front of said dial connected to so as to rotate with said disk, said indicator and disk being angularly adjustable relative to said dial and being rotated therewith by said driving means, and a handle connected to said indicator and having limited movement relative to said dial whereby said indicator and disk may be adjusted relative to said dial and said dial may be angularly adjusted.

7. In a time switch, a switch, driving means, an angularly adjustable dial rotated by said driving means and having a portion of increased radius, a disk rearwardly of said dial and having a portion of increased radius, an indicator in front of said dial and connected to said disk so as to rotate therewith, said disk and indicator being angularly adjustable relative to said dial, and a handle connected to said indicator and having limited movement relative to said dial whereby said indicator and disk may be adjusted relative to said dial and said dial may be angularly adjusted, said switch having an element adapted to follow the contour of the peripheries of said disk and dial.

8. In a time switch, driving means, a switch, an angularly adjustable dial rotated by said driving means and having a portion of increased radius provided at its forward end with an inclined edge, a disk rearwardly of said dial and having a portion of increased radius with its rear edge inclined oppositely to the forward edge of the portion of increased radius of said dial, an indicator in front of said dial and connected to said disk so as to rotate therewith, said dial having numerals thereon chronologically arranged in a direction reverse to that in which said driving means rotates said dial, a fixed pointer cooperating with the numerals on said dial, said disk and indicator being angularly

adjustable relative to said dial, and a handle connected to said indicator and having limited movement relative to said dial whereby said indicator and disk may be adjusted relative to said dial and said dial may be angularly adjusted, said switch having an element adapted to follow the contour of the peripheries of said disk and dial.

9. In a time switch, a switch, driving means, a dial rotatable by and angularly adjustable relative to said driving means and having means for controlling the throwing of said switch into one condition, a disk rearwardly of said dial and having means for controlling the throwing of said switch into another condition, means for frictionally engaging said disk against said dial whereby the same are rotated in unison by said driving means, an indicator in front of said dial and connected to so as to rotate with said disk, said indicator and disk being angularly adjustable relative to said dial and movable in unison therewith by said driving means, and a handle connected to said indicator and having limited angular movement relative to said dial whereby said indicator and disk may be adjusted relative to said dial and said dial may be adjusted by turning said handle.

10. In a time switch, a switch, driving means, a dial having means on its periphery for controlling the throwing of said switch into one condition at any predetermined time, a clutch between said driving means and dial through which said driving means drives said dial and permitting of angular adjustment of said dial relative to said driving means, a disk rearwardly of said dial adjustable relative thereto and having means on its periphery for controlling the throwing of said switch into another condition at any predetermined time, means for frictionally engaging said disk against said dial, an indicator in front of said dial connected so as to rotate with said disk, said indicator and disk being angularly adjustable relative to said dial and being rotated therewith by said driving means, and a handle connected to said indicator and having limited movement relative to said dial whereby said indicator and disk may be adjusted relative to said dial and said dial may be angularly adjusted.

11. In a time switch, a switch, driving means having a driven shaft, a sleeve journaled on said shaft, a friction clutch between said sleeve and shaft, a dial connected to said sleeve and having a portion of increased radius, a disk rearwardly of said dial and having a portion of increased radius, means for frictionally holding said disk against the rear face of said dial, an indicator in front of said dial and connected to said disk so as to rotate therewith, said disk and indicator being angularly adjustable relative to said dial, and a handle journaled on said sleeve connected to said indicator and

having limited movement relative to said dial whereby said indicator and disk may be adjusted relative to said dial and said dial may be angularly adjusted, said switch having an element adapted to follow the contour of the peripheries of said disk and dial.

12. In a time switch, driving means, a switch, a dial rotated by said driving means and angularly adjustable relative thereto, 10 said dial having means for controlling the throwing of said switch into one condition at any predetermined time, an indicator rotated in unison with said dial by said driving means, said indicator being angularly 15 adjustable with respect to said dial, means movable with said indicator for controlling the throwing of the switch into another condition at any predetermined time, a fixed pointer cooperating with said dial, a single 20 handle for adjusting said indicator and dial, and means for limiting the extent of rotation of said dial and indicator.

13. In a time switch, a switch, driving means, a dial rotated by and angularly adjustable relative to said driving means and having means for controlling the throwing of said switch into one condition, a disk rearwardly of said dial and having means for controlling the throwing of said switch into 25 another condition, an indicator in front of said dial and connected to so as to rotate with said disk, said indicator and disk being angularly adjustable relative to said dial and movable in unison therewith by said driving 30 means, a handle connected to said indicator and having limited angular movement relative to said dial whereby said indicator and disk may be adjusted relative to said dial, and said dial may be adjusted by turning said 35 handle, and a stop on said dial for preventing rotation thereof when the same has reached zero position.

14. In a time switch, a switch, driving means, an angularly adjustable dial rotated 45 by said driving means and having a portion of increased radius, a disk rearwardly of said dial and having a portion of increased radius, an indicator in front of said dial and connected to said disk so as to rotate there- 50 with, said disk and indicator being angularly adjustable relative to said dial, a handle connected to said indicator and having limited

movement relative to said dial whereby said indicator and disk may be adjusted relative to said dial and said dial may be angularly 55 adjusted, said switch having an element adapted to follow the contour of the peripheries of said disk and dial, a pointer cooperating with said dial for indicating the setting thereof, and a stop on the periphery of 60 said dial adapted to engage said pointer and thereby prevent further rotation of said dial and disk.

15. In a time switch, a switch, driving means, an angularly adjustable dial rotated 65 by said driving means and having a portion of increased radius, a disk rearwardly of said dial and having a portion of increased radius, an indicator in front of said dial and connected to said disk so as to rotate therewith, 70 said disk and indicator being angularly adjustable relative to said dial, and a handle connected to said indicator and having limited movement relative to said dial whereby 75 said indicator and disk may be adjusted relative to said dial and said dial may be angularly adjusted, said switch having an element adapted to follow the contour of the peripheries of said disk and dial, said dial having a shoulder against which said switch element 80 is adapted to engage to hold said dial against rotation in a given position.

16. In a time switch, a clock or equivalent mechanism having a driven shaft, a switch, a dial having means for opening said switch 85 at any predetermined time, a friction clutch between said dial and said shaft, a disk having frictional engagement with said dial whereby the disk is rotated with the dial when the latter is driven through said clutch, 90 said disk having means for controlling the throwing "on" of said switch, an indicator connected to said disk and angularly adjustable therewith relative to said dial, a handle connected to said indicator, means for limiting the angular adjustment between said dial 95 and indicator, and a pointer cooperating with said dial, the frictional engagement between said disk and dial being less than that exerted by said clutch whereby said clutch will hold 100 said dial stationary while said indicator is angularly adjusted relative to the dial.

GEORGE HEGEMAN HART.
